UNITED STATES PATENT OFFICE.

CHRISTIAN STEENSTRUP, OF SCHENECTADY, NEW YORK, ASSIGNOR TO GENERAL ELECTRIC COMPANY, A CORPORATION OF NEW YORK.

ELASTIC-FLUID TURBINE.

1,353,797.

Specification of Letters Patent. Patented Sept. 21, 1920.

Application filed February 16, 1920. Serial No. 359,077.

To all whom it may concern:

Be it known that I, CHRISTIAN STEENSTRUP, a citizen of the United States, residing at Schenectady, county of Schenectady, 5 State of New York, have invented certain new and useful Improvements in Elastic-Fluid Turbines, of which the following is a specification.

The present invention relates to elastic 10 fluid turbines and particularly to bucket or blade fastening means.

In applying buckets to a bucket-carrying element, for example, to the rim of a turbine wheel, particularly when the fastening 15 means is of the so-termed inverted dovetailed type, it is desirable that the adjacent sides of the bucket bases engage each other around the periphery of the wheel so tightly as to set up stresses in the buckets of 20 such a magnitude that when the wheel is rotating, the centrifugal forces set up will not be sufficient to stretch the buckets to an extent which would cause the buckets to separate from each other around the wheel. In 25 other words, it is desirable that the sides of the bucket bases engage each other with sufficient pressure to set up a tension in the buckets themselves equivalent, at least, to the stress that will be applied by centrifugal 30 force when the machine is in operation. Likewise, it is desirable that the bottoms of the bucket bases engage the annular shoulders at the base of the rim with sufficient pressure, so that the stress set up is 35 equivalent, at least, to the stress that will be applied by centrifugal force when the machine is in operation, so that the bucket bases will not separate from the shoulders. However, it is essential, on the other hand, that 40 initial stresses of too great magnitude should not be set up in the bucket ring when the buckets are being put on the wheel, as this may result in improper positioning of the buckets and in injury to the wheel and to the 45 buckets.

The object of my invention is to provide an improved structure and arrangement whereby it is only possible to set up initial stresses in the bucket rings of a desired 50 magnitude, and to this end I provide crushing strips along the edges of the buckets, or along their bottoms, or both, which, when the stresses reach a certain value, will crush, thereby preventing the stresses set up from 55 exceeding such value.

For a consideration of what I believe to be novel and my invention, attention is directed to the accompanying description and the claims appended thereto.

In the drawing, Figure 1 is a radial sectional view of a portion of a turbine motor having bucket fastening means embodying my invention; Fig. 2 is a side elevation of the arrangement shown in Fig. 1; Fig. 3 is a section taken on line 3-3 Fig. 1; Figs. 4 and 5 are views similar to Figs. 1 and 2 of a modification, and Fig. 6 is a radial sectional view of a further modification.

In Figs. 1, 2 and 3 my invention is illustrated as applied to a bucket structure of the type wherein the bucket-carrying member 9, shown as being a wheel, has a rim 10 which is provided on opposite sides with annular concentric undercut grooves providing ridges or projections 11 which slope or incline toward the center of the member 9. At the base of rim 10 are shoulders 12. The buckets are indicated at 13 and their bases are U-shaped, being provided with legs 14 which straddle rim 10. The inner sides of legs 14 are provided with ridges or projections 15 which are adapted to fit into the undercut grooves on rim 10, the ridges 11 and 15 thus interlocking. Buckets of this particular type may, according to one known method, be assembled on the wheel rim by making the bucket base legs 14 sufficiently wide apart that the same may be slipped radially astraddle the rim 10 after which the legs are squeezed together and the buckets 90 are moved radially to bring ridges 15 and 11 into engagement. According to this method the entire ring of buckets is first assembled around the wheel in a temporary manner and in correct spaced relation to each other, 95 after which the bucket legs of each bucket are squeezed or pressed together toward the rim, the buckets at the same time being displaced outwardly, thereby interlocking ridges 11 and 15. Now, during this squeezing 100 operation, the metal of the bucket base legs flows circumferentially and in some cases this has had the effect of pressing adjacent buckets together so tightly that stresses would be set up in the bucket ring 105 greatly in excess of that desired. Also, when the bucket legs are squeezed together, the ridges 15 in moving radially outwardly, slide up the outer surfaces of ridges 11 and are crushed up by said ridges, and the fric-

110

tion brought about by this action causes at times, ridges 15 to flow circumferentially and engage so tightly the surfaces of the next adjacent buckets as to prevent the radial movement of ridges 15 to correct positions under ridges 11. The result is an imperfect interlocking of ridges 15 and 11.

According to my invention, I overcome the above referred to difficulties by providing crushing strips 16 between the bucket bases which serve to reduce the area of contact between adjacent buckets so that regardless of the amount of pressure that may be applied on the sides of the buckets, stresses exceeding a predetermined value cannot be set up in the bucket ring since if such stresses are exceeded, strips 16 will be crushed. At the same time, the crushing strips 16 serve to space apart slightly adjacent buckets at the ends of the ridges 15 so that even though such ridges do flow circumferentially somewhat during the squeezing-up operation, they will not come into engagement with adjacent buckets so as to prevent radially outward movement. In other words, ridges 15 will not flow circumferentially sufficiently during the squeezing-up operations to frictionally engage and lock themselves against the next adjacent buckets.

By the provision of such crushing strips, therefore, I am enabled to guard against excessive stresses being set up in the bucket ring when the buckets are assembled after the manner described but still I am enabled to obtain the desired degree of stress in the bucket ring. At the same time I overcome a serious difficulty which has heretofore been encountered in assembling buckets on a rotor by the method referred to, due to the ridges or projections on the bucket legs flowing sidewise and binding against adjacent bucket surfaces.

After the bucket legs have been squeezed onto the wheel rim there are small spaces left between the inner end of the bucket legs and shoulders 12, and these spaces may be filled by upsetting the ends of the bucket legs, or the material of the shoulders or by driving in a separate calking strip. In the present instance, the spaces are shown as being filled by a separate calking strip 17.

Referring now to Figs. 4 and 5, an inverted dovetail fastening means is shown of the type wherein the buckets are put on the rim of the wheel through filling slots and moved around into correct spaced relation to each other, the bases of adjacent buckets being brought into engagement with each other, or with suitable spacing blocks located between the bucket bases. 20 indicates a bucket wheel having a rim 21 provided with an annular head 22 which forms projections 23. The buckets 24 are provided with U-shaped bases comprising legs 25 which

straddle rim 21 and have projections 26 which fit under projections 23. At the base of rim 21 are annular shoulders 27 against which the inner ends of bucket legs 25 rest, and at 28 are annular flanges which prevent the bucket legs from spreading laterally. Between adjacent buckets are crushing strips 29 similar to crushing strips 16 of Figs. 1 to 3 and at the inner ends of the bucket base legs are crushing strips 30 located between the bottoms of such legs and flanges 28.

In carrying out my invention in connection with a wheel structure, as shown in Figs. 4 and 5, I first mount the ring of buckets on the wheel rim in the usual manner, the filling openings being closed by blocks as is well understood. When so assembled, the bucket bases are in nice engagement with each other. I now take a suitable calking tool and calk a number of the buckets at spaced intervals around the wheel so as to set up a tension in the buckets themselves equivalent or substantially equivalent to the stresses that will be applied by centrifugal force when the machine is in operation. Stresses beyond a predetermined amount cannot be set up in the bucket ring by calking, however, as strips 29 will be crushed. I also calk the wheel 95 along the side surfaces of shoulders 27 so as to drive these shoulders out radially and bring projections 26 firmly into engagement with projections 23, and by utilizing crushing strips 30 I avoid the possibility of setting up stresses of too great a value in rim 21 and the legs of the buckets. During this latter calking operation a small amount of material may be forced up or caused to flow into the spaces between crushing strips 30 105 as indicated at A in Fig. 5 and this assists in locking the buckets into position.

Crushing strips 30 may extend either crosswise or circumferentially as found desirable. In Figs. 4 and 5 I have shown them 110 as extending crosswise while in Fig. 6 I have shown a modified arrangement in which they extend circumferentially.

In Fig. 6, 20^a indicates the bucket-carrying member, 24^a the buckets, and 29^a and 30^a the crushing strips corresponding to crushing strips 29 and 30 of Figs. 4 and 5. In this connection it will of course be obvious that crushing strips as shown at 30 and 30^a in Figs. 4 to 6 inclusive, may be 120 used in connection with a structure as shown in Figs. 1 to 3 inclusive if found desirable.

In accordance with the provisions of the patent statutes, I have described the principle of operation of my invention, together with the apparatus which I now consider to represent the best embodiment thereof, but I desire to have it understood that the apparatus shown is only illustrative, and 130

that the invention may be carried out by other means.

What I claim as new and desire to secure by Letters Patent of the United States, is:

5. 1. In an elastic fluid turbine, a bucket-carrying member, and buckets thereon which are provided with crushing strips.
10. 2. In an elastic fluid turbine, a bucket ring having crushing pieces between adjacent buckets.
15. 3. In an elastic fluid turbine, a bucket-carrying member having a rim, and buckets having bases which straddle said rim, said buckets being provided with crushing strips which serve to limit the stresses set up in the bucket ring.
20. 4. In an elastic fluid turbine, a bucket-carrying member having a rim with ridges thereon, buckets which straddle said rim and have ridges which interlock with said first named ridges, and integral crushing strips located between adjacent surfaces of the buckets.
25. 5. In an elastic fluid turbine having a bucket-carrying member provided with a rim and shoulders, buckets having bases which are attached to said rim and terminate at said shoulders, and crushing strips between the bottoms of the bucket bases and said shoulders.
30. 6. In an elastic fluid turbine having a bucket-carrying member provided with a rim and shoulders, buckets having bases which are attached to said rim and terminate at said shoulders, crushing strips between the bottom of the bucket bases and said shoulders, and crushing strips between adjacent surfaces of the buckets.
35. 7. In an elastic fluid turbine, a bucket ring having buckets provided with crushing strips along their sides and at their bottoms.

In witness whereof, I have hereunto set my hand.

CHRISTIAN STEENSTRUP.
